Attorney

UNITED STATES PATENT OFFICE.

HENRY CLAY CLARK, OF SOUTH NORWOOD, OHIO.

COLLAR HOOK.

Application filed February 7, 1922. Serial No. 534,723.

To all whom it may concern:

Be it known that I, HENRY CLAY CLARK, a citizen of the United States, residing at South Norwood, in the county of Hamilton and State of Ohio, have invented a new and useful Improvement in Collar Hooks, of which the following is a specification.

My invention relates to the fastening of a collar to a shirt neck-band flap, and has for advantage allowing the collar to slip in buttoning the first side of the collar; also in allowing slippage, taking up slack in first button when buttoning the second side of the collar.

15 A further object of the invention is to allow perfect slippage of the neck-tie. The hook being flat in construction, prevents pressure on the vertebrae of the wearer. The curved end of the hook prevents same 20 from becoming detached from the collar.

In the drawings:

Figure 1 is a perspective view of the collar hook;

Fig. 2 is a side view showing the slightly curved ends of the hook.

Fig. 3 is a view of the blank from which the hook is made.

The collar hook is formed from a strip of sheet metal having slight resiliency and flexibility. As shown in the drawings, the strip is somewhat wider at the point indicated by the letter *a*, than at the point *b*. The point *a* indicates the termination of a finger adapted to be inserted beneath the flap of a neck band of a shirt. As shown, this finger is curved slightly to conform to the curvature of the vertebrae upon which it bears.

40 The letter *b*, indicates the curved end of a finger adapted for insertion in the rear collar button hole of a collar, said curved end taking under the lower edge of the inner

flap of the collar so as to prevent accidental detachment of the collar from the hook or shirt.

As shown, the finger which engages the neck-band flap and is designated by the letter *a* is somewhat wider than the collar engaging finger, thus giving a relatively broad bearing surface at the point of contact with the vertebrae. The relatively narrow end snugly engages the collar button hole.

In forming the collar hook, the strip is folded upon itself at a point near its transverse center, the remaining longer end then being folded upon itself at a point substantially one-half its length. The extreme end of the last named end is curved as at *b*, so as to engage the lower edge of the inner fold of a collar.

It is understood that certain minor changes in the details of construction may be resorted to within the scope of the appended claim.

What I claim is:

A device of the character described comprising an elongated strip of sheet metal, said strip being folded upon itself at a point substantially midway of its length to provide a finger adapted to be inserted beneath the flap of a neck band on a shirt, the remaining portion being folded upon itself at a point near its transverse center, the extreme end being curved inwardly as shown to take under the lower edge of the inner flap of a collar after being passed through the rear button hole of said collar, said curved end and adjacent portions being narrower than the first named finger and snugly engaging the collar button hole, and said first named finger being curved substantially as shown to conform with the curvature of the vertebrae at the point of contact.

HENRY CLAY CLARK.
